UNITED STATES PATENT OFFICE

2,222,537

HEATER

Orval A. Law, Roscoe, Ill.

Application July 30, 1937, Serial No. 156,591

1 Claim. (Cl. 237—12.3)

This invention appertains to new and useful improvements in heaters, especially adapted for use on automobiles.

The principal object of the present invention is to provide a heater for use on automobiles, wherein the exhaust line of the engine is used as the heat source.

Another important object of the invention is to provide a hot water heater especially adapted for use on automobiles, aircraft, and elsewhere, which can be used in operation over an extensive period of time without requiring repair or replacement or replenishment of its fluid content.

These and various other important objects and advantages of the invention will become apparent to the reader of the following specification.

In the drawings:

Figure 1 represents a fragmentary side elevational view of the engine portion of an automobile with its parts broken away to show the heater installed.

Figure 2 is a top plan view of the radiator.

Figure 3 is a vertical sectional view through the boiler.

Figure 4 is a horizontal sectional view on line 4—4 of Figure 3.

Referring to the drawings, wherein like numerals designate like parts, it can be seen in Figure 1 that the numeral 5 generally refers to the automobile construction which includes the usual cowl wall 6 to the rearward side of which is secured the radiator structure generally referred to by the numeral 7.

The numeral 8 generally refers to the boiler, while the numeral 9 denotes the reservoir.

The exhaust manifold is denoted by the reference 9' and has the exhaust pipe 10 extending therefrom. The boiler 8 is interposed between portions of the exhaust pipe 10 and consists of the outer shell 11 and the internal shell 12 spaced from the shell 11. This spacing of the shells is maintained through the use of upper and lower necks 13—14 extending from the internal shell 12, the outer ends of these necks 13—14 being flanged as at 15 and these flanges overlap the central portions of the ends of the outer shell, the parts being suitably secured together such as by welding. Threaded apertures are formed in the flanges of adjacent portions of the outer shell 11 for receiving screws 15' which connect the flanges 10' of the upper and lower portions of the pipe 10 to the upper and lower ends of the boiler. Of course, the two spaced shells 11 and 12 form a dead-air space for insulating the chamber formed by the inner shell through which the

exhaust gases pass as they leave the upper portion of the pipe 10 to reach the lower portion of said pipe.

Into the upper portion of the shell 12 extends the pipe line 16 connecting to the vertical water coil 17 in the shell 12. The lower end of this coil 17 extends outwardly of the shell 12 and shell 11 to form the line 17' to the reservoir 9. The lower portion of the reservoir 9 is of the hopper type, while the top is open and a drain cock 18 is provided in the lower portion of the line 17'.

The radiator 7 is shown in Figure 2 and consists of an elongated shell 19 supported by brackets 20 on the back board 21 located on the cowl 15 wall 6. The pipe line 16 extends into the shell 19 and through the longitudinal partition 24 therein which terminates in the shell 19 in spaced relation to one end thereof to allow a by-pass 22. The shell 19 is thus divided into the side with 20 which the pipe line 16 communicates and the side with which the return line 22 communicates, the line 22 extending to the top of the reservoir 9. A duct line 23 extends from the radiator to the reservoir 9 so that excessive steam can escape 25 from the radiator to the reservoir. This line 23 connects with the radiator at a point adjacent the point where the inlet pipe 16 discharges into the radiator as will be seen in Figure 2. This pipe 23 extends upwardly and then downwardly 30 to form a loop with its discharge end extending into the water in the reservoir. Thus, if an excessive amount of steam is formed at the inlet end of the radiator this steam will pass into the pipe 23 where practically all of the steam will be 35 condensed as it enters the looped portion and this water of condensation will be returned to the system, the hot water flowing through the radiator, of course, returning to the reservoir through 40 the pipe 22. This pipe 23, therefore, acts to remove steam or an excessive quantity of steam from the radiator and condenses the steam so that the water in the system will not boil away as fast as it would if this pipe 23 is not used.

The shells 11 and 12 can be formed in any suitable manner to permit the insertion of the coil 17 though I prefer to form the shells in sections which will permit the coil to be put in place after which the sections of the shells are welded together.

While the foregoing specification sets forth the invention in specific terms, it is to be understood that numerous changes in the shape, size, and materials may be resorted to without depart-

ing from the spirit and scope of the invention as claimed hereinafter.

Having described the invention, what is claimed as new is:

- 5 A heating system for a motor vehicle comprising a boiler including a water receiving coil, means for heating the coil by the products of combustion from the motor, an elevated water containing reservoir, a pipe connecting the lower end of the reservoir with an end of the coil, a radiator, an inlet pipe connecting the other end of the coil
- 10

with the radiator, a third pipe connected with the radiator adjacent the point where the inlet pipe delivers the fluid into the radiator and said third pipe extending upwardly to a point above the reservoir where the pipe is formed with a loop, with the pipe extending from the loop part into the reservoir and below the water level thereof and a return pipe connecting the radiator with the top of the reservoir.
